CLAIM

The ornamental design for a toner cartridge, as shown and described.

DESCRIPTION

FIG. 1 is a left side, front, top perspective view of a toner cartridge showing the new design;

FIG. 2 is a right side, rear, top perspective view thereof;

FIG. 3 is a right side, front, bottom perspective view thereof;

FIG. 4 is a left side, rear, bottom perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The features shown in broken lines depict portions of the toner cartridge that form no part of the claimed design.
